UNITED STATES PATENT OFFICE

CHARLES HAROLD PETSKEYES, OF CINCINNATI, OHIO

DESIGN FOR A SANDPAPERING-MACHINE CASING

Application filed March 17, 1930. Serial No. 34,945. Term of patent 7 years.

To all whom it may concern:

Be it known that I, CHARLES HAROLD PETSKEYES, a citizen of the United States, residing at Cincinnati, in the county of Hamilton and State of Ohio, have invented a new, original, and ornamental Design for Sandpapering-Machine Casing, of which the following is a specification, reference being had to the accompanying drawing, forming a part hereof.

The figure is a perspective view of a sandpapering machine casing, showing my new design.

I claim:

The ornamental design for a sandpapering machine casing, as shown.

CHARLES HAROLD PETSKEYES.
